HEAT MEASURING INSTRUMENT

William E. Engelhard, R.D. 1, Apalachin, N.Y.

Filed Dec. 1, 1961, Ser. No. 67,775

Term of patent 14 years

(Cl. D52—6)

FIG. 4

FIG. 3

FIG. 1 is a perspective view of a heat measuring instrument embodying my new design;

FIG. 2 is a side elevational view thereof; the side opposite is identical to that shown in FIG. 2; FIG. 3 is a bottom plan view thereof.

FIG. 4 is a front elevational view thereof with the cable and probe omitted for convenience of illustration.

It is to be understood that the solid line portions of the cable in FIG. 1 are repeated throughout its length. In FIGS. 2, 3 and 4 portions of the coupling, cable and probe have been omitted for convenience of illustration.

I claim:

The ornamental design for a heat measuring instrument, as shown and described.
